UNITED STATES PATENT OFFICE

EDWARD J. VON PEIN, OF DAYTON, OHIO, ASSIGNOR TO THE NATIONAL CASH REGISTER COMPANY, OF DAYTON, OHIO, A CORPORATION OF MARYLAND

CASH REGISTER

Original application filed November 16, 1923, Serial No. 675,158. Divided and this application filed June 14, 1926. Serial No. 115,903.

This invention relates to improvements in printing mechanism adapted for use with cash registers and like machines.

The subject matter of this application constitutes a division of the co-pending application of the same inventor, Serial No. 675,158, filed November 16, 1923.

One object of this invention is to provide an improved method of operating a plurality of printer impression hammers.

With this and incidental objects in view, the invention consists of certain novel features of construction and combinations of parts, the essential elements of which are set forth in appended claims and a preferred form or embodiment of which is hereinafter described with reference to the drawings which accompany and form part of this specification.

20 Of said drawings:

Fig. 1 is a transverse section of the machine taken to the left of the totalizer.

Fig. 2 is a detail view of the driving connection between the key coupler and the cam shaft.

Fig. 3 is a sectional view taken between the right side frame and the printer frame, showing a portion of the printer impression hammer mechanism.

30 Fig. 4 is a side elevation of the printer mechanism, and a part of the driving mechanism.

Fig. 5 is a side elevation of the interlock mechanism, shown in the moved position.

35 *In general*

The mechanism disclosed is the same as that shown in the co-pending application referred to. Only so much of the general mechanism is disclosed here as is necessary to give an understanding of these improvements, and the same will be described only in so far as is necessary to understand the specific invention here involved.

45 The machine includes a plurality of groups of amount or item keys, a totalizer, item entering, item printing and item indicating mechanisms, and a driving means. The keyboard includes a plurality of groups of item or amount keys 20 pivoted on a transverse rod

21 mounted in the side frames of the machine. The rear ends of the keys are adapted to engage a key coupler 22 which swings on trunnions 23 journaled in the side frames of the machine. Actuator operating arms 24, connected to the rear ends of the keys, are adapted to engage rods 25 carried by rocker frames connected to totalizer actuators 26.

The totalizer actuators are normally in mesh with gears 27, connected with the item printing wheels 28 (Fig. 4) by a tube line to set up the amounts represented by the keys depressed. The key coupler 22 carries a roller 29 mounted on its right hand side (Fig. 2) which cooperates with a slot in a driving double rack 30. The driving double rack rotates a shaft 31 in the usual manner, as is well known in the art.

The amounts represented by the keys depressed are also entered in a totalizer 37 mounted in a frame 38 (Fig. 1) pivotally supported on trunnions 39 supported in a frame cross bar of the machine.

The totalizer is of a well known form for this type of machine, and is provided with 75 totalizer elements having pinions 40 engaging the actuators 26 at the proper time, to enter the items registered by the keys.

Resting on the rear ends of the keys 20 are the usual tablet indicators 41 which are elevated to display positions when the keys are operated.

A driving shaft 59 (Figs. 3 and 4) is rotated in a counter-clockwise direction by a gear 71 secured to the shaft and in mesh with a pinion 72 secured to a sleeve 73 freely mounted on a stud 74 supported by the printer frame 75. The pinion 72 may be driven by a crank 76, clutched to the sleeve 73. The crank 76 is shown in broken lines in Fig. 4, and illustrated and described in a Von Pein Patent No. 1,664,955, dated April 3, 1928.

95 *Interlocking mechanism*

As the item keys and the driving means must be operated in a certain sequence, an interlock is provided between these two operating means. Secured to the right hand trunnion of the key coupler, outside the printer 100

frame 75, is an arm 80 (Fig. 4) carrying a pin 81 which connects the arm 80 with an arm 82 pivotally mounted upon the trunnion 23. The lower end of the arm 82 carries a roller 83 contacting the upper edge 84 of a lever 85 fulcrumed on a stud 86 projecting from the printer frame 75. The lever 85 is provided with a rearwardly extending arm 88, normally held in the path of a lug 89 on the side of the gear 71, by an arm 92, pivoted on the trunnion 23. A stud 91, on the arm 92, is held against the forward end of the lever 85, as shown in Fig. 4, by a spring 98 stretched between a stud on the arm 92 and a stud 99 on the frame 75, the stud 99 projecting through a notch 100 in the lever 85. The spring 98, through the stud 91, tends to cam the lever 85 clockwise, but this movement of the lever 85 is limited by the contact of the right-hand wall of the notch 100 with the stud 99, and therefore, the counter-clockwise movement of the arm 92 is limited by the stud 91 contacting the forward edge of the lever 85. Thus, the spring 98, through the arm 92 and stud 91, holds the lever 85 in a position as determined by the stud 99, in which position the arm 88 prevents rotation of the gear 71, and, consequently, prevents rotation of the cam shaft 59.

As the arm 82 is rocked counter-clockwise by the key coupler, the roller 83 wipes across the top of the lever 85 and in this manner the lever 85 is moved counter-clockwise to cause the rearwardly extending arm 88 of the lever 85 to move out of the path of the lug 89 secured to the gear 71.

The counter-clockwise movement of the lever 85, acting on the stud 91, rocks the arm 92 clockwise until the forward edge of the lever 85 passes the stud 91, whereupon the arm 92 is rocked counter-clockwise by the spring 98, until the stud 91 rests on the end 90 of the lever 85, as shown in Fig. 5.

After the arm 82 has been returned to its normal position, the arm 92 maintains the lever 85 in the moved position. The left wall of the notch 100 contacts the stud 99 when the lever 85 is moved to the position shown in Fig. 5, thus limiting the counter-clockwise movement thereof, and since the stud 91 rests against the end 90 of the lever 85, the movement of the arm 92 is also limited by the stud 99.

With the lever 85 in this operated position (Fig. 5) the driving crank 76 previously referred to is free to rotate the driving shaft 59. As this shaft rotates counter-clockwise, the lug 89, which has a projecting nose 93, contacts the lower arm 94 of the lever 85 and forces this lever to return to its normal position, in which position the driving means will be disabled when the lug 89 again contacts the arm 88.

The clockwise movement of the lever 85 to its normal position, removes the end 90 there-

of from beneath the stud 91 (Fig. 5), and the spring 98 causes the stud 91 to follow the underside of the lever 85 until the lever 85 reaches its normal position (Fig. 4), with the right side of the notch 100 in contact with the stud 99, thus, again limiting the movements of the lever 85 and arm 92.

Another interlocking feature is provided, which allows but one operation of the item keys to each operation of the driving means. A spring-actuated arm 95, pivotally mounted upon the stud 86, has a laterally projecting pin 96 engaging a shoulder formed on the lever 85. As the lever 85 is moved counter-clockwise, as previously described, the arm 95 will engage the pin 81 (see Fig. 5) and rest upon this pin during the counter-clockwise movement of the arm 82. During the return or clockwise movement of the arm 82, the arm 95 will move counter-clockwise until the pin 96 again engages the shoulder on the lever 85, in which position an end 97 of the arm 95 will be in the path of the pin 81 to prevent a second movement of the arm 82 by the operation of an item key. The return of the lever 85 to its normal position will return the arm 95 to the position shown in Fig. 4.

Printing mechanism

Only so much of the printing mechanism is disclosed in Fig. 4 as enters into the invention here involved, the printer being fully described and illustrated in the Von Pein application Serial No. 675,158, previously referred to. The type wheels 28, previously described, print the items as they are entered, both upon a record strip 103 retained within the machine and an issuing strip 104.

The record strip 103 is fed from a supply 105 around guide rollers 106 and onto a receiving roll 107 in the usual manner. The issuing strip 104 is fed from a supply roll (not shown) around a guide roller 108 and between a feeding roller 109 and a tension 110 roller 110. The tension roller 110 is carried on a pivoted arm 111 and held in contact with the feeding roller 109 by a spring 112.

The feeding roller 109 moves counter-clockwise at each operation of the machine, and retrograde motion of this roller is prevented by a spring-actuated pawl 113 which engages a ratchet wheel 114 secured to the feeding roller 109. This feeding roller is secured to a shaft 115 journaled in the printer frame 75. The feeding roller is operated by a spring-tensioned pawl 116 (Fig. 3) cooperating with a ratchet wheel 102 pinned to the shaft 115. The pawl is pivoted on a lever 117 pivotally mounted upon the shaft 115. Secured to this lever is a pinion 118 which meshes with a segment arm 119 pivoted on a stud 120 supported by the frame work of the machine. This arm 119 is oscillated at each operation of the machine by two cams 121

and 122 engaging rollers 123 and 124, respectively, which are mounted upon studs carried by the segment arm 119.

The records are made upon the record strip 103 and the issuing strip 104 by the aid of an inking ribbon 125 which passes partly around a feeding roller 126, over guide rollers supported in the printer frame and under a tension roller 131 carried by an arm 132 pivoted at a point 133.

10 The impressions upon the record strip and the issuing strip are made simultaneously by spring-actuated impression hammers 134 and 135. Impression hammer 134, which causes the impression to be made upon the record strip 103, is pivoted upon a stud 136 mounted in the printer frame and has an ear 137 engaging a spring plunger 138 supported in a bracket 139 secured to the printer frame. 15 A downwardly extending arm 140 from the impression hammer 134 contacts a pin 141 (Figs. 3 and 4) to return the impression hammer 134 to its normal position and retain it in such position after an operation.

20 25 The impression hammer 135, which causes the impression to be made upon the issuing strip 104, is pivoted upon a stud 146 supported by the printer frame, and has a rearwardly extending arm with a lug 147 engaging a spring-actuated plunger 148 supported by a bracket 149 secured to the printer frame. An upwardly extending arm 150 from the impression hammer 135 contacts a pin 151 which returns the impression hammer 135 to its normal position and retains it there after an operation of the machine.

25 30 The pins 141 and 151 are carried by a lever 152 (Fig. 3) which is fulcrumed on a stud 153 supported by the frame of the machine. 40 This lever 152 has a flat sided pin 154 which engages a spring-pulled latch 155 pivoted on a stud 156. This latch retains the lever 152 in its normal position, as shown in Fig. 3, and the impression hammers 134 and 135 under spring tension, as shown in Fig. 4. As 45 the shaft 31 (Fig. 3) rotates counter-clockwise during the operation of any item key 20 (Fig. 1), a pin 158 carried by a disk 157 secured to the shaft will engage an arm 159 extending downwardly from the latch 155, and cause the latch to move clockwise on its pivot and become disengaged from the flat 50 sided pin 154. At this time a cam 161 engages a nose 160 on the lever 152 and retains the impression hammers until the shoulder 55 55 of the cam 161 passes the nose 160 which then permits the spring plungers 138 and 148 (Fig. 4) to operate the impression hammers 134 and 135 to print upon the record strip 103 and the issuing strip 104.

60 The purpose of having the nose 160 on the lever 152 quickly drop from the high part of the cam 161 to the low part, is to afford a springing hammer blow upon the type 65 wheels.

During the operation of the driving mechanism the impression hammers are returned to their normal positions by an upwardly extending arm 168 of the segment arm 119 (Fig. 3). As this arm is moved counter-clockwise, the arm 168 will engage the flat sided pin 154 and return the lever 152 to a position to enable the latch 155 to again engage the flat sided pin 154 and retain the impression hammers in their normal positions until the next operation of the machine.

Operation

In operating the machine, the operator depresses the item keys 20 corresponding to the value of the transaction, and allows them to return to normal positions. This causes the item to be entered in the totalizer, displayed by the indicators and printed on the record strip and the issuing strip. 80 Operation of the keys 20 also releases the driving shaft 59 which is then operated by the crank 76, to complete the transaction by feeding the issuing strip and restoring the impression hammers to normal position, and operating other parts of the mechanism.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, in combination, item entering means, a type carrier adapted to be positioned by said item entering means, an impression hammer adapted to make an impression from said type carrier, means for normally retaining said hammer under tension, a latch for holding said retaining means effective, means operated by said item entering means for releasing said latch to permit the impression hammer to operate, a driving means operated separately from said item entering means, and means operated by said driving means for returning the hammer retaining means to normal position, and through the returning movement of said hammer retaining means, returning said impression hammer to normal position.

2. In a machine of the class described, in combination, item entering means, a type carrier adapted to be positioned by said item entering means, an impression hammer normally under spring tension and adapted to cooperate with said type carrier to make impressions, a swinging member normally effective to hold said impression hammer in normal position, a latch engaging said swinging member to retain it in normal position, means operated by said item entering means for releasing said latch, a driving means operated separately from said item entering

means, and means operated by said driving means to restore said swinging member to its normal position.

3. In a machine of the class described, the combination of a plurality of lever keys, type carriers adapted to be positioned by said lever keys, a single impression hammer normally under spring tension and adapted to cooperate with said type carriers to make an impression, a pivoted member adapted to hold said impression hammer in normal position, a latch engaging said pivoted member to retain it in normal position, means operated by said lever keys for releasing said latch, a driving shaft operated separately from said lever keys, and a pivoted member operated by means secured to said driving shaft for operating said first pivoted member to return said impression hammer to its normal position.

4. In a machine of the class described, the combination of a plurality of lever keys, a type carrier adapted to be positioned by said lever keys, an impression hammer normally under spring tension and adapted to cooperate with said type carriers to make an impression, a pivoted member adapted to hold said impression hammer in normal position, a latch engaging said pivoted member to retain it in normal position, means operated by said lever keys for releasing said latch, a driving shaft operated separately from said lever keys, a pivoted member operated from said driving shaft for returning said impression hammer to its normal position, means for normally disabling said driving shaft, means operated by said lever keys to render said disabling means ineffective on the depression of said keys, and means for maintaining said disabling means in the ineffective position after said item keys return to normal.

5. In a machine of the class described, in combination, item entering means, a type carrier adapted to be positioned by said item entering means, a plurality of normally retracted, spring-pressed impression hammers adapted to make impressions from said type carrier, means for normally retaining said hammers under tension, a latch for holding said retaining means effective, means operated by said item entering means for releasing said latch to permit the impression hammers to operate, a driving means operated separately from said item entering means, means operated by said driving means for returning said impression hammers to normal positions, means for normally disabling said operating means, and means to render said disabling means ineffective by the operation of said item entering means.

6. In a machine of the class described, the combination of a plurality of lever item keys, type carriers adapted to be positioned by said keys, an impression hammer normally under spring tension and adapted to cooperate with said type carriers to make an impression,

means for retaining said impression hammer in normal position, means operated by said keys for releasing said hammer from said retaining means, a crank-operated means for returning said hammer to normal retaining position, means for normally disabling said crank-operated means, means to render said disabling means ineffective by the operation of said item entering means, and means preventing a second operation of said item entering means until after an operation of said crank-operated means.

In testimony whereof I affix my signature.

EDWARD J. VON PEIN.
